KNIFE

Elmer Hyatt, Cleveland, Ohio

Application October 21, 1939, Serial No. 300,647

4 Claims. (Cl. 30—153)

This invention, as indicated, relates to a knife structure. More particularly, it comprises a knife structure wherein a plurality of elements pivoted together form the means for moving the blade into open and closed position, and locking the same in each of said positions, and forming the handle of the knife after full movement to either open or closed position. The invention also includes a knife wherein the use of springs is eliminated, and wherein a portion of the body of the knife serves as a locking element for the same. The invention also includes a simple method of manufacturing a knife structure wherein multiple bladed knives may be provided, and wherein also two single units may be combined through the use of a single pivot pin in providing a knife structure having a plurality of blades.

The principal object of the present invention is to provide a knife structure having a body member, a blade, and a guard so related that the same cooperate to lock the blade in open and closed position.

Another object of the invention is to provide a knife structure wherein a body and a guard element associated therein may be formed of strip material readily fabricated at a minimum of cost and providing a housing for the blade when in closed position, or as a means for opening the blade and thereafter locking the same when in open position.

Another object of the invention is to provide a knife structure which may be formed as a single unit or united through the use of one or more common pivot pins into a multiple series of units having the desired number of blades.

Other and further objects of the invention will appear in the course of the following description.

To the accomplishment of the foregoing and related ends, said invention, then, consists of the means and method hereinafter fully described and particularly pointed out in the claims, the annexed drawing and the following description setting forth in detail certain structures and methods embodying the invention, such disclosed means constituting, however, but several of various forms in which the principle of the invention may be used.

In said annexed drawings:

Fig. 1 is a plan view drawn to actual size showing a single bladed knife embodying the principles of the invention:

Fig. 2 is an edgewise view as seen from the lower edge of the structure illustrated in Fig. 1.

Fig. 3 is a perspective view of the structure shown in Figs. 1 and 2 with the blade in full open

position and the guard ready to be moved to full closed position for locking the blade and forming the handle for the device.

Fig. 4 is a plan view of the structure shown in Figs. 1 to 3 with the blade in full open position and the guard locked to the handle and locking the blade in its open position.

Fig. 5 is a plan view of a modified form of knife structure embodying the principles of the invention wherein a double bladed knife is provided, the blades being pivoted at opposite ends of the body member.

Fig. 6 is an edgewise view as seen from the lower portion of the structure illustrated in Fig. 5.

Fig. 7 is a plan view showing the knife structure illustrated in Figs. 5 and 6 with the blade and guard members thereof in partly open position.

Fig. 8 is a plan view of a multiple bladed knife wherein the blades are mounted on a common pivot point, and wherein the body of the knife is made up of double strip members permitting the conversion of such knife into two single units through the provision of an independent pivot pin for each of such units.

Fig. 9 is an edgewise view as seen from the lower edge of the structure illustrated in Fig. 8.

Fig. 10 is a plan view of the structure shown in Figs. 8 and 9 showing the handle and blades in partly open position; and

Figs. 11 and 12 are exploded perspective views showing in detail the pivot construction with lugs and blade tang in their various positions during the cycles of opening and closing.

As is clearly shown in Figs. 1 to 4 of the drawings, and also in the exploded perspective views comprising Figures 11 and 12 my preferred type of knife structure comprises a body member 1, preferably formed of a strip of sheet material bent backwardly upon itself to form a boss 2, and having at its free edge, downwardly turned portion 3 spacing said boss from the adjacent portion of the body. Through the provision of notches 4 on each side of the turned over portion of the strip, means for holding a terminal ring 5 in operative relation to the body is provided. The boss is preferably provided with a notch 6 of V-shaped outline as seen from above, said notch being in the form of a triangular perforation through the strip of metal. The body portion of the structure is preferably provided with recesses 7 on opposite side edges at a point spaced slightly from the boss 2 to permit free operation of the guard member, as will be presently described. The body portion opposite the position of the boss is preferably provided with an integral lug

8 struck upwardly, said lug forming a limit stop for the blade when in open position.

Cutaway corners 9 may be provided at the end of the body portion adjacent said lug. Said body portion is also provided with an aperture 10, slightly offset from the center toward said lug 8 to receive a pivot pin 11 upon which a guard member 12 and a blade 13 are pivotally mounted. The blade member may have substantially the same form as an ordinary knife blade, but in order to provide for compactness of structure such blade may be formed with a V-shaped notch 14, such notch providing a recess for receiving the operative lug 15 provided on the end of the guard member. If desired, an additional lug 16 may be provided on the guard member on the same side with and spaced from the lug 15 heretofore described. Said lug member 16 serves as a blade retaining element when the knife is in closed position. Cutaway ends 18 may be provided on the guard member adjacent the pivot pin, one of said ends carrying the downwardly turned blade operative lug 15. It should be noted that the lug 15 is of the full thickness of the blade and may ride upon the inner face of the body member, particularly when the guard is moved to fully open or fully closed position. Through the engagement of said lug with the body member an adequate degree of resiliency is provided against which the spring portion of the guard member may react while being moved frictionally over the boss 2 to interlocking engagement with the notch 6 heretofore described in order to insure safe locking engagement with said notch. The guard member is provided with a triangular projection 19 of a size to snugly fit the notch 6, and to be held resiliently therein through the spring action of the guard member 12.

The inner face of the guard member 12 may be provided with a serrated surface providing a nail file, and the projecting triangular projection 19, besides serving the function of a locking element for the device, may be used as a finger nail cleaning device when the guard member is opened into parallelism with the body member at one-half of its full path of travel.

In order to have the parts rotate about the pivot pin with adequate clearance for the lugs the pivot pin may be offset slightly from the central line of the assembled structure, where a narrow width of knife structure is desired, but where a greater width is in view the pivot pin may be placed exactly in the center.

In the modified type of my structure, shown in Figs. 5 to 7, inclusive, the body 21 may be provided with a boss 22 which may be secured to the body by means of a locking element provided by the head of a set-screw 23 and will hold the guard member 24 which is provided with a suitable aperture 25 to engage thereover, the apertured end of the guard being bent inwardly to a slight extent to provide blade clearance and a resilient engagement with the head of the set-screw 23. The guard member 24 is engaged with the body member 21 by means of a pivot pin 26 which also serves as the pivot for the knife blade 27 which is disposed between the body member and the guard member. The pivot pin 26 may be in the form of a screw-threaded stud 28 screw-threadedly engaging the body member at the end provided with the boss and having a lock nut 29 to securely hold the parts in central relation. The knife blade, it will be noted in Fig. 7, will have the sharp edge downwardly when closed, and a limit stop 30 will hold the blade in closed alignment with the body 75

portion. The blade is moved to closing position by means of a lug 31 on the guard member which will engage the back edge of the knife blade as it is turned to closing position and remove such blade into the closed position just described, the aperture 25 being then locked over the stud 23, heretofore described. The opening of the blade is brought about through the action of a stud 32 on the guard member adjacent its pivoted end which bears against the underside of the blade structure adjacent the pivot point.

Substantially a similar guard and blade construction may be provided at the opposite end of the body member just described, there being 15 an additional boss 33 with a pivot pin 34 engaged therein at the opposite end thereof similar to the pivot pin 26, heretofore described, such pivot pin holding a blade 35 and a guard member 36 in pivoted relation to the body on the opposite side from the blade and guard member heretofore described. The blade 35, as shown in Fig. 7, when closed will have its cutting edge turned in an upward direction, whereas the blade 27 heretofore described has its cutting edge turned in a downward direction when positioned in the manner shown in Fig. 7. The guard member 36 is provided with an aperture 37, and has studs 38, 39, adjacent the pivot point to move the blade to closed and open position respectively. A lug 40 on the body serves as a limit stop for the blade when in open position; the lug 38 in addition to moving the blade into closed position serves to hold the same locked against accidental displacement when the aperture 37 is engaged over the stud 38. 30 The studs 32 and 39 (Figs. 5 to 7) correspond in position and function to the lug 15 (Figs. 1, 2, 3, 4, 11, and 12) in opening the knife blade, and also in applying locking spring tension to the end of the guard member opposite the end on which it is mounted. The studs 31 and 38 (Figs. 5 to 7) are closure locks for the blade corresponding in position and function to the lug 16 (Figs. 1, 2, 3, 4, 11, and 12).

The modified form of construction shown in 45 Figs. 8, 9 and 10 provides a doubled bladed knife somewhat similar to the knife shown in Figs. 5 to 7, but in place of having a pivot pin for the blades at each end of the body member, having a single pivot pin upon which two blade members and two body members are pivoted. This construction, 50 similar to the construction shown in Figs. 5 to 7, may be converted into a pair of knife structures through the removal of a pivot pin and the clamping of each set of parts together by means of individual pins. The body member is preferably formed of two members 51, 52, which may be interlocked with each other by means of a tongue 53 having an aperture 54 for a chain or the like, such tongue engaging within a loop extension 55 formed on the companion body member 52. A boss 56 may serve as an ornamental handle element when secured to the sides of the respective body members. The body members will lie parallel to each other in interlocked relation while 55 the knife is utilized as a double bladed knife which, by using suitable blades offset to coact with each other; the body members 51, 52, may serve as the handle element of a shear with the blades coacting with each other as shear blades. The body member is provided at the end opposite the handle just described with a pivot pin 57, upon which are engaged blade members 58 associated with a guard member 59 on the outer side of the body member 51 and with a blade member 61 and an associated guard member 62 on the outer side

of the body member 52. Each of the guard members 59 and 62 may be provided with a blade opening and closing sets of lugs 63, 64, respectively, and may be formed with eyes 65, 66, on opposite sides of the guard members 62 and 59, respectively, to permit easy opening of such guard members by the user. The lugs 63 (Figs. 8 to 10) correspond in position and function to the lug 15 (Figs. 1, 2, 3, 4, 11, and 12) and to the studs 32 and 39 (Figs. 5 to 7), and the lugs 64 (Figs. 8 to 10) correspond in position and function to the lug 16 (Figs. 1, 2, 3, 4, 11, and 12) and to the studs 31 and 38 (Figs. 5 to 7), as set forth above.

Opposite the eyes 65, 66, the guard members are cut away providing recesses 67, 68, respectively, to permit easy access to the eye on the companion guard member. Each guard member at its extreme end is turned downwardly to provide a locking flange 69 having teeth 71, 72, engaging on opposite sides of the body member adjacent the handle 56. The body members may have narrow neck portions 73, 74, to permit free access to the eye portions of the guard members.

Other modes of applying the principle of my invention may be employed instead of those explained, change being made as regards the structure and method herein disclosed, provided the means stated by any of the following claims or the equivalent of such stated means be employed.

I therefore particularly point out and distinctly claim as my invention:

1. A device of the character described having in combination a body member, a blade member pivoted to one end of said body member of resilient strip material, and a guard member mounted on the pivot of said blade member, and having integral marginal struck-up lugs cooperating with said body member, one of said lugs bearing frictionally on said body member to increase the lock-

ing spring tension on said guard, and said lugs engaging said blade member to move said blade to open and closed position, respectively.

2. A device of the character described having in combination a body member, a boss adjacent one end of said body member providing a locking seat, and a guard member of resilient strip material pivoted to the opposite end of said body member, having at its end adjacent said pivot a bearing member to ride frictionally over the body member to apply locking spring tension to the guard member when said guard member is moved into closed engagement with said boss.

3. A device of the character described having in combination a body member, a blade member and a flexible guard member pivoted to said body member, a boss providing a locking element on said body member, means associated with said members to permit movement of said guard member over a 360 degree path of movement to open and closed position and said blade member over a path of movement of 180 degrees to open and closed position, and a bearing lug on said guard member adjacent said pivot to force the free flexible end thereof into engagement with the locking element of said boss for locking said blade and guard members in open and closed position.

4. A pocket knife having a handle portion made of strip metal of a resilient character and comprising a body member and a guard member cooperating therewith, a pivot pin engaged in offset relation through said body member and guard member, a blade member mounted on said pivot pin between the same, cooperating locking elements on the free ends of said body member and said guard member, respectively, and a bearing lug on said guard member adjacent said pivot to force said locking elements into engagement.

ELMER HYATT.
